UNITED STATES PATENT OFFICE.

MINARD A. POSSONS, OF CLEVELAND, OHIO, ASSIGNOR TO AMERICAN STOVE COMPANY,
OF ST. LOUIS, MISSOURI, A CORPORATION OF NEW JERSEY.

GAS-RANGE.

1,160,755.

Specification of Letters Patent. Patented Nov. 16, 1915.

Application filed December 23, 1914. Serial No. 878,722.

REISSUED

To all whom it may concern:

Be it known that I, MINARD A. POSSONS, a citizen of the United States, residing at Cleveland, in the county of Cuyahoga and 5 State of Ohio, have invented certain new and useful Improvements in Gas-Ranges, of which the following is a specification, reference being had therein to the accompanying drawing.

10 My invention relates to improvements in gas ranges.

The object of my invention is to provide a gas range in which a broiler burner is arranged in the upper portion of the oven and 15 whereby a damper is so arranged that it is open when the gas supply to the broiler burner is open and closed when the gas supply to the broiler burner is closed. This is essential owing to the fact that in broiling 20 it is necessary to have some escape for the smoke and when it is also necessary to close up the oven when baking, which result follows from the structure herein later described.

25 Another object of my invention is to provide a simple and effective arrangement having certain details of structure and combination of parts hereinafter fully described.

In the accompanying drawings, Figure 1 30 is a perspective view, in dotted lines, of the upper end of an oven showing my improvement applied thereto. Fig. 2 is a side elevation, partly broken away, showing the arrangement of the gas valve for the broiler 35 burner and the gas valve for the baking burner. Fig. 3 is a perspective view of a gas oven similar to that shown in Fig. 1, but showing the lock between the gas valve for the broiler burner and the gas valve for the baking burner, whereby but one burner 40 can be used at a time. Fig. 4 is an enlarged side elevation of Fig. 1, showing the oven in section. Fig. 5 is a perspective view of my improved damper.

45 Referring now to the drawings, 1 represents the oven which has arranged adjacent its upper end the broiler burner 2, which is supplied with gas through the pipe 3 leading from the valve 4. This valve 4 is of the

50 turning-plug type having the plug 5 provided with a handle 6 at its outer end and by means of which the gas is turned on and off to the broiler burner 2. The oven 1, to the rear just above the broiler burner 2, is 55 provided with an opening 7, provided with a

guide-way 8 on which is slidably mounted the damper 9. This damper is preferably of sheet metal having a series of openings 10, adapted to register with corresponding openings in the oven, whereby the proper 60 ventilation for the escape of the smoke for the upper end of the oven is provided. Secured to the enlarged portion 11 of the damper 9 is a rod 12, which extends outwardly and is provided with an eye 13, at 65 its outer end on the outside of the oven. The side of the oven adjacent the said rod is provided with brackets 14 and 15, in which is mounted the oscillating rod 16, which has at its outer end the bracket 14 and 70 downwardly turned portion 17. This portion 17 enters the eye 13 and by oscillating the rod 16, the rod 12 is oscillated for opening and closing the damper 9.

The end of the rod 16 on the outside of 75 the bracket 15 is provided with a downwardly turned portion 18, which is connected to the curved arm 19 by means of a cotter-pin 20. The turning plug 5 of the valve 4 is provided with a rigidly extending arm 21, to which the lower end of the link 19 is connected by the cotter-pin 22. By this arrangement it will be seen that the turning of the plug 5 to the left by means 80 of the handle 6 to open the valve allows the gas to pass through the pipe 3 to the broiler burner, throws the arm 21 upwardly and through the medium of the link 19, the rod 16 is rocked. This rocking of the rod 16 through the medium of the rod 12 causes the damper 9 to move in a position so that the 85 openings 10 register with the openings in the rear wall of the oven, whereby the smoke and the like may pass from the oven. In stoves of this character it is very essential 90 that this damper be closed when the baking burner is in operation and in order to facilitate this, I have provided the structure above mentioned. In ovens of this character it is also very essential that the broiler burner 95 be out of operation when the baking burner is in operation, for the reason that it often happens that the gas is turned on to the broiler burner and is not ignited, and when the baking burner is lighted there occurs an 100 explosion in the oven. In order to prevent the two burners from being turned on at the same time, I have provided the structure 105 shown in Figs. 3 and 4.

The valve 23 for supplying the gas to the 110

baking burner has its turning plug 24 extended outwardly and provided with a handle 25 by means of which the plug is turned. The said turning plug is provided 5 with outwardly extending guide ears 26 and 27, and on the inside of these ears, is provided with an enlarged portion 28. Surrounding this enlarged portion is an elongated plate member 29, having a circular 10 opening 30 within which turns the member 28. Extending upwardly within the plate 29 is an elongated slot 31, which communicates with the circular opening 30. Connected to the upper end of the plate 29 is a 15 rod 32, which has its upper end connected by a cotter pin 33 to a rigid arm 34, carried by the turning plug 5 of the broiler burner.

When the turning plug 24 of the baking burner is turned in a position to supply gas 20 to the said baking burner, the enlarged portion 28 carried thereby is in a position transverse the enlarged circular openings 30, and locks the rod 32 against movement. Thus it will be seen that the turning plug 5 of the 25 broiler burner cannot be operated and thus gas cannot be supplied to the broiler burner when the valve of the baking burner is open. When the valve of the baking burner is turned, the enlarged portion 28 carried by 30 the turning plug 24 registers with the elongated slot 31 and thus the turning plug 5 can be turned as the plate 29 travels downwardly around the member.

Having thus described my invention what 35 I claim and desire to secure by Letters Patent is:

1. The combination with an oven having a baking burner, a gas supply valve for said burner, a broiler burner in the oven, a 40 gas supply valve for the broiler burner, a damper in the oven, and means operated by the gas supply valve of the broiler burner for opening the damper when the valve is open and closing the damper before the 45 valve for the baking burner is opened.

2. The combination with an oven, of a baking burner in the lower end of the oven, a broiler burner in the upper end of the oven, gas supply valves for said burners, a 50 damper for the oven, and means operated by the gas supply valve of the broiler burner for opening the damper when the valve is open and closing the damper before the valve of the baking burner is opened.

3. The combination with a gas oven having a baking burner in its lower end, a gas supply valve for said burner, a broiler burner in the upper end of the oven, a gas supply valve for the broiler burner, a damper 55 for the oven, and means connecting the gas supply valve of the broiler burner and the damper, whereby the damper is opened when the broiler burner valve is open and closed before the valve of the baking burner 60 is opened.

4. The combination with a gas range having a baking burner in its lower end, a gas supply valve for said burner, a broiler burner in the upper end of the oven, a gas supply valve for the broiler burner, a damper 70 for the oven, means operated by the movement of the gas supply valve of the broiler burner for opening the damper when the valve is opened and closing the damper when the valve is closed, and means connecting the two valves whereby but one valve is allowed to be opened at the same time.

5. The combination with a gas range having a baking burner in its lower end, a 80 gas supply valve for said burner, a broiler burner in the upper end of the oven, a gas supply valve for the broiler burner, a damper for the oven, means connecting the gas supply valve of the broiler burner with 85 the damper for opening the damper with the opening of the valve and closing the damper with the closing of the valve, and a rod connecting the gas supply valve of the broiler burner with the gas supply valve of 90 the baking burner, whereby both valves cannot be opened at the same time.

6. The combination with a gas range having a lower baking burner, a gas supply valve for the said burner, a broiler burner 95 in the upper end of the oven, a gas supply valve for the broiler burner, a damper for the oven, means connecting the gas supply valve of the broiler burner with the damper for opening the damper with the 100 opening of the valve and closing the damper with the closing of the valve, and a rod pivotally connected to the valve stem of one valve and having a keyhole slot connection with the valve stem of the other valve, 105 whereby both valves cannot be opened at the same time.

7. The combination with a gas range having a lower baking burner, a valve for said burner, a broiler burner within the upper 110 end of the oven, a gas supply for the said burner, a damper for the oven, means connecting the gas supply valve of the broiler burner with the damper for opening the damper when the valve is opened and closing the damper when the valve is closed, a projection carried by the valve stem of one 115 valve, a rod pivotally connected to the said projection, the valve stem of the other valve having a transverse member carried thereby and working in a keyhole slot in the lower end of the rod, whereby both valves cannot be opened at the same time.

8. The combination with a gas range having a baking burner, a gas supply valve for the said burner, a broiler burner in the upper end of the oven, a gas supply valve for the said burner, a damper for the oven, means connecting the damper and the valve 125 for the broiler burner, whereby the damper 130

is opened with the opening of the valve and closed with the closing of the valve, an arm carried by the valve stem of one valve, a rod pivotally connected to the said arm, a transverse member carried by the valve stem of the other valve and lower end of the rod having an elongated portion provided with a keyhole slot and adapted to receive the transverse member carried by the valve stem,

whereby both valves cannot be opened at the same time.

In testimony whereof I hereunto affix my signature in the presence of two witnesses.
